UNITED STATES PATENT OFFICE

105,886

DESIGN FOR A MENDING CABINET

George E. Melown, Youngstown, Ohio

Application June 11, 1937, Serial No. 69,793

Term of patent 7 years

To all whom it may concern:

Be it known that I, George E. Melown, a citizen of the United States, residing at Youngstown, in the county of Mahoning and State of Ohio, have invented a new, original, and ornamental Design for a Mending Cabinet, of which the following is a specification, reference being had to the accompanying drawing, forming part thereof.

The figure is a perspective view of a mending cabinet showing my design.

I claim:

The ornamental design for a mending cabinet as shown.

GEORGE E. MELOWN.
